(57) **CLAIM**

The ornamental design for a LED display device, as shown and described.

DESCRIPTION

FIG. 1 is a front view of the LED display device according to the first embodiment showing our new design;

FIG. 2 is an enlarged front view thereof shown broken away for ease of illustration;

FIG. 3 is an enlarged right side view thereof;

FIG. 4 is an enlarged left side view thereof;

FIG. 5 is an enlarged front view of a center section shown in FIG. 1;

FIG. 6 is an enlarged rear view thereof;

FIG. 7 is an enlarged top plan view thereof;

FIG. 8 is an enlarged bottom view thereof;

FIG. 9 is an enlarged front perspective view thereof;

FIG. 10 is an enlarged rear perspective view thereof;

FIG. 11 is an enlarged sectional view taken along line “11—11” in FIG. 5;

FIG. 12 is an enlarged sectional view taken along line “12—12” in FIG. 5;

FIG. 13 is a first reference view showing an alternate configuration;

FIG. 14 is a second reference view showing an alternate configuration;

FIG. 15 is a front view of the LED display device according to the second embodiment;

FIG. 16 is an enlarged front view thereof shown broken away for ease of illustration;

FIG. 17 is an enlarged right side view thereof;

FIG. 18 is an enlarged left side view thereof;

FIG. 19 is an enlarged front view of a center section shown in FIG. 15;

FIG. 20 is an enlarged rear view thereof;

FIG. 21 is an enlarged top plan view thereof;

FIG. 22 is an enlarged bottom view thereof;

FIG. 23 is an enlarged front perspective view thereof;

FIG. 24 is an enlarged rear perspective view thereof;

FIG. 25 is an enlarged sectional view taken along line “25—25” in FIG. 19;

FIG. 26 is an enlarged sectional view taken along line “26—26” in FIG. 19;

FIG. 27 is a first reference view showing an alternate configuration; and,

FIG. 28 is a second reference view showing an alternate configuration.

The broken lines in the drawing are shown for illustrative purpose only and form no part of the claimed design.
